WO DM/103 611 8/2018

Primary Examiner — Kelley A Donnelly

(57) **CLAIM**

The ornamental design for an elongated alternate rail body of a tool holding device, as shown and described.

DESCRIPTION

FIG. 1 is a top perspective view of an elongated alternate rail body of a tool holding device showing my new design;

FIG. 2 is a bottom perspective view thereof;

FIG. 3 is a front elevational view thereof; the rear view being a mirror image;

FIG. 4 is a top plan view thereof; and,

FIG. 5 is a right side elevational view thereof; the left side being a mirror image.

The left side elevational view is a mirror image of the right elevational view.

The rear elevational view is a mirror image of the front elevational view.

The broken line showing the elongated alternate rail body of a tool holding device in FIGS. 1-3 are included for the purpose of showing environmental structure and form no part of the claimed design.

1 Claim, 5 Drawing Sheets
